UNITED STATES PATENT OFFICE

ROBERT F. RINGLE, OF ZELIENOPLE, PENNSYLVANIA

MOLDING MACHINE

Application filed May 29, 1929. Serial No. 366,862.

My invention refers to improvements in molding machines of the general type illustrated in prior patent of Austin and Ringle No. 1,243,030, of October 16, 1917. It has 5 in view to provide means for making operative engagement between the raising and lowering equalizing table and the flask for accurate engagement therebetween and for lowering the flask from the pattern after 10 molding, and reversal of the flask.

Also, to provide an improved construction of cylinder for rotating the turnover shaft by mounting it on trunnions whereby to avoid the necessity of an intervening connecting rod, and also by a novel arrangement 15 of elevating mechanism for the equalizing table, utilizing a pair of raising and lowering cylinders located at opposite sides of said shaft, together with other features of construction and advantages in operation, as 20 shall be more fully hereinafter described.

The complete molding machine and the present improvement are embodied in an entire operative mechanism including the jarring 25 ring table on which the flask and its contained sand are vibrated or agitated, turnover mechanism by which the flask and the packed sand surrounding the pattern are elevated away from the jarring table and 30 rotated one half revolution for location above the lowering mechanism, and such lowering mechanism and equalizing table and the actuating means therefor, as mentioned above.

In the drawings illustrating one preferred 35 embodiment of the invention:

Fig. 1 is a general view in elevation, partly in section and partly broken away, showing the several main elements of the installation;

Fig. 2 is an end view of the same in elevation;

Fig. 3 is a partial view in elevation, similar to Fig. 1, showing the turnover arms and plate erected and with the equalizing table raised in supporting position underneath the 45 reversed flask;

Fig. 4 is a plan view of the machine.

The turnover and flask lowering mechanism is generally indicated at A and is in operative relation to the jarring machine B, 50 both of which are of well known construction

and generally similar to the apparatus shown in the above mentioned patent and also in a companion application filed herewith, Serial No. 366,864.

The jarring machine B is provided with 55 the usual table 2 upon which the flask 3 is supported with the intervening pattern supporting turnover plate 4. These elements, as well as the vibrating mechanism for jarring the table, are of well understood construction 60 and operation, and need not be further described.

The turnover plate 4 is provided at each 65 end with lateral socket projections 5 having tapered sockets for engagement by tapered trunnions 6 of the usual turnover arms 7 by which the plate 4 and flask 3 are swung over upwardly above the withdrawing and equalizing table, as indicated in Fig. 3.

Arms 7 are mounted on rock-shaft 8 extending across in bearings 9 of the main frame of the machine and operatively connected by lever 10 by pivotal connection 11 with plunger rod 12 of plunger 13 of oscillating cylinder 14.

Cylinder 14 is provided with laterally arranged supporting trunnions 15 carried in bearings 16 at each side of the rear middle portion of the main frame, whereby the cylinder is adapted to automatically adjust itself 80 angularly to the varying positions of lever 10, in either raising or lowering the arms 7.

Cylinder 14 is provided with a pressure supply conduit 17 preferably having a flexible connection with a source of supply, and under proper valve control for admission of fluid pressure in raising the arms and their supported turnover plate and flask. Re-active pressure may be supplied by conduit 18 in reversing the operation, the lowering however being mainly effected by gravitation against the cushioning action of the contained impelling fluid subject to release by proper valve manipulation.

As shown, the cylinder 14 is mounted about 95 midway across the main foundation frame of the machine, and is free to swing in either direction through suitable clearance between its bearings.

Rotation of the turnover plate 4 and flask 100

3 is effected by restraining or limiting action of controlling rods 19 pivotally mounted at 20 and connected at 21 with trunnions 6 so that, as the turnover arms swing upwardly 5 and over, the position of the flask is reversed above the equalizing table, as shown.

Flask 3 is provided with the usual bottom board and battens against which the contacting elements of the equalizing table engage 10 when elevated.

Equalizing table 22 comprises a middle supporting base plate portion having oppositely projecting extensions 23 which are fixedly mounted upon the upper ends of 15 plungers 24 of cylinders 25, located at opposite sides of the middle of the machine, and of the axial center of cylinder 14.

Cylinders 25, as shown, are off-set at diagonally opposite positions on one side and the 20 other of shaft 8 for clearance, and are mounted upon the main foundation or bed plate D of the machine. By such construction, when fluid pressure is simultaneously applied to the cylinders, the plungers 24 will be raised together, maintaining the equalizing table in 25 a horizontal position at all times.

Cylinder 25 is provided with a supply conduit 26 with suitable valve control for raising and lowering the plungers at desired 30 speed. A supplemental similarly controlled conduit 27 supplies pressure to the lower extension 28 of cylinder 25, provided with a buffering spring 29 for cushioning the plungers at the termination of their downward 35 movement.

As shown, the table 22—23 is bolted to the upper end of opposite plungers 24, and these are provided with surrounding protecting shells 30 in telescoping engagement with co- 40 acting shells 31, for exclusion of dust or other foreign matter.

Table 22—23 is provided along each side with resiliently mounted contact bars or rails 32 having upper contacting edges for engagement against the under side of the battens or other surface portions of the under side 45 of the reversed flask 3. The rails 32 are so mounted that their contacting edges will independently engage against the surface to be supported and will automatically adjust themselves thereto, one independently of the other, upon coming into contact therewith, whereby to entirely support the flask when fixed in such position for positive and accurate lowering thereof, without danger of 50 harmful variation of the flask and molded sand in withdrawal from the pattern.

For such purpose each rail is mounted by portions intermediate of its ends upon resisting cushioning springs 33 seated in casings 34 therefor of the rails, and bearing downwardly against the upper side of the equalizing table by terminal caps 35.

As thus constructed, as the equalizing table 55 is brought upwardly into contact with the

under side of the inverted flask and with the slight pressure present at the upward end of the stroke of plungers 24, each rail will automatically accommodate itself to such under side, either in parallelism or with more or less deflection at one side or the other or both, dependent on any corresponding variation in one or the other or both sides of the flask bottom. 70

For the purpose of positively fixing the rails in such adjusted position so as to temporarily hold them in proper contacting relation with the flask during lowering movement thereof, by release of pressure from cylinders 25, I provide the holding mechanism for the rails illustrated in Fig. 4. The rails themselves lie inwardly against or in close proximity to the outer side faces of upstanding posts or abutments 36, arranged along each side of the middle portion 22 of the equalizing table, against which the rails are to be tightly clamped and held against accidental or other movement during lowering of the table. 75

For such purpose I provide a lever 37 having transverse adjusting bolts 38—39, pivotally connected at 40 with inwardly extending lugs of rails 32. The opposite end of lever 37 is connected at 41 with the terminal of piston rod 42 of the plunger 43 in cylinder 44, mounted on the table, as in Fig. 4. When it is desired to fixedly hold the rails 32 in tight abutting contact with posts 36, pressure is applied to plunger 43 by flexibly connected conduit 45 from any source of pressure, subject to the opening and closing of a suitable control valve, not shown, at any convenient location within reach of the operator. 90

When thus tightly clamped, and the flask 105 3 has been released from the turnover plate by removal of clamps 46, the flask resting evenly and stably on the edges of rails 32 may be positively and evenly lowered downwardly below the pattern so that the turnover plate may then be returned to its initial position over the bumper, and the pattern removed for substitution by an additional pattern and flask. 110

The lowering of the flask under control of the valve or valves of conduits 26—27 is at first comparatively slow and then more rapidly, or for any desired variation in speed under control of the operating valve, as will be readily understood. 115

The construction and operation of the invention will be readily understood and appreciated from the foregoing description, and it will be found to be continuously efficient and to avoid the usual objections and trouble incident to improper or variable lowering of the flask, avoiding any even slight variation, and resulting in a perfectly formed mold cavity. 125

The accurate raising and lowering of the 130

equalizing table is facilitated and improved by the use of the plural cylinders located and operating as described, while the mounting of the turnover cylinder 14 insures accurate and reliable operation, and the cylinder itself is entirely self-contained and direct-
5 acting on the shaft levers.

What I claim is:—

1. Turnover and flask withdrawing mechanism for a molding machine comprising a turnover plate, turnover arms and an actuating shaft therefor having an operating lever, a pivotally mounted cylinder having a plunger directly connected with the lever, an equalizing table above the cylinder, and plungers and cylinders therefor one on each opposite side of the actuating shaft.

2. Turnover and flask withdrawing mechanism for a molding machine comprising a turnover plate, turnover arms and means effecting partial rotation of the plate, an actuating shaft for the turnover arms having a lever, a cylinder provided with trunnion bearings and a plunger having a stem directly connected with the shaft lever, means supplying pressure to the cylinder, an equalizing table above the cylinder, and plungers and cylinders therefor arranged at diagonally opposite positions one on each side of the actuating shaft.

3. In a molding machine, the combination with a pair of turnover arms operatively connected with a turnover plate adapted to locate a flask on a bumping machine and to elevate it in reversed position above an equalizing table, an operating shaft for the turnover arms, means for actuating said arms, and an equalizing table provided with a plurality of elevating and lowering cylinders and plungers diagonally arranged one on each opposite side of the operating shaft.

4. In a molding machine, the combination with a pair of turnover arms operatively connected with a turnover plate adapted to locate a flask on a bumping machine and to elevate it in reversed position above an equalizing table, a shaft operatively connected with the turnover arms and having a lever, a plunger directly connected with said lever and provided with a trunnion supported cylinder, a cylinder located at each diagonally opposite side of the shaft having a plunger, and an equalizing table on said plungers.

5. In a molding machine, the combination with a pair of turnover arms operatively connected with a turnover plate adapted to locate a flask on a bumping machine and to elevate it in reversed position above an equalizing table, a shaft operatively connected with the turnover arms and having a lever, a plunger directly connected with said lever and provided with a trunnion supported cylinder, a cylinder located at each diagonally opposite side of the shaft having a plunger, and an equalizing table on said plungers provided

with resiliently mounted flask supporting elements.

6. In a molding machine, the combination with a pair of turnover arms operatively connected with a turnover plate adapted to locate a flask on a bumping machine and to elevate it in reversed position above an equalizing table, a shaft operatively connected with the turnover arms and having a lever, a plunger directly connected with said lever and provided with a trunnion supported cylinder, a cylinder located at each diagonally opposite side of the shaft having a plunger, and an equalizing table on said plungers provided with resiliently mounted flask supporting elements and means for holding them fixedly in position.

7. In combination, a supporting frame, a rotating shaft having endmost bearing supports thereon, turnover arms on the ends of said shaft connected with a turnover plate and having reversing rods connected therewith, an oscillating cylinder mounted in trunnion bearings and provided with a plunger, lever arms on the shaft between its bearings directly connected with the plunger, a pair of diagonally located plunger cylinders one at each diagonally opposite side of the shaft provided with raising and lowering plungers, and an equalizing table mounted on said plungers having flask engaging supports.

8. In combination, a supporting frame, a rotating shaft having endmost bearing supports thereon, turnover arms on the ends of said shaft connected with a turnover plate and having reversing rods connected therewith, an oscillating cylinder mounted in trunnion bearings and provided with a plunger, lever arms on the shaft between its bearings directly connected with the plunger, a pair of diagonally located plunger cylinders one at each opposite side of the shaft provided with raising and lowering plungers, and an equalizing table mounted on said plungers having flask engaging supports and means providing for independent movement of said supports and for fixedly holding them in position.

In testimony whereof I hereunto affix my signature.

ROBERT F. RINGLE.
